 ors to Celanese Corporation of America, a cor-
 poration of Delaware

Application December 12, 1931, Serial No. 580,596
 In Great Britain January 26, 1931

5 Claims. (Cl. 66—126)

This invention relates to knitting machines, and particularly to flat knitting machines, in which a weft thread is fed successively to the needles by a guide which travels alternately in opposite directions along the knitting course.

5 In machines of this kind, for example, flat fashioned stocking machines, whether of the reciprocating needle type or of straight bar type, feeding of the thread to the needle is closely followed by further operations of knitting, for example, the sinking of loops of thread round the needles and (in the case of sliding needle machines) the operation of the needles themselves under the influence of the knitting cams to knit the thread into loops. For this purpose it is necessary that the yarn guide in its traverse along the knitting course should proceed in advance of the means for effecting the knitting traverse, i. e. the needle cams and/or sinker cams (hereinafter referred to as "knitting cams"), which operate to knit the yarn thus fed. It is an object of this invention to provide means for effecting the motion of the yarn guide in correct relationship to the knitting cams in whichever direction the yarn guide and knitting cams are moving.

30 According to the present invention, the yarn guide of a knitting machine is driven in the same direction as the knitting cams through the medium of means which lead the yarn guide in advance of the knitting cams in either direction of their movement. The means provided at each end of the knitting traverse may be such as to bring the yarn guide gradually to rest while the knitting cams pass it, the yarn guide thus being ready to move in advance of the knitting cams when they commence their motion in the reverse direction. The yarn guide is preferably driven by the means for traversing the knitting cams in such a manner that the yarn guide is positively driven along the knitting traverse, and the reversal of lead occurring at the end of each traverse is positively accomplished.

45 A suitable method of connecting the yarn guide to the knitting cams comprises the use of a pair of links pivoted to the yarn guide traverse means and adapted to be engaged in turn at their ends by a pair of abutments in connection with the means for effecting the knitting traverse. Thus, 50 stops may be provided at each end of the knitting traverse to disengage the link from the one abutment, and then to allow the other link to engage with the other abutment when the lead is reversed. The abutments may be in the form of 55 ramps, out of engagement with which the ends

of the links ride on coming against the stops at either end of the traverse. Means may be provided if desired in connection with such links and their attachment with the yarn guide traversing mechanism whereby the amount of lead of the yarn guide over the knitting cams may be adjusted. This may be done by adjusting either the pivot points of the links, or the positions of the abutments engaging the ends of the links. It is generally convenient that the lead of the yarn 10 guide should be the same in both directions of travel.

55 Where stops are employed at the ends of the knitting traverse, as described above, the position of the stops at each end of the knitting 15 traverse will be determined by the width of the fabric to be produced. In fully fashioned machines adapted to knit fabrics or articles of varying widths the reversing stops may be automatically adjusted during knitting to correspond 20 with the variation in width of the fabric, as described in U. S. Patent No. 1,902,151. For this purpose the fashioning means already in use to effect narrowing of the fabric may be adapted to operate also the reversing stops, or alternatively, 25 separate mechanism may be used preferably controlled by the same pattern wheel or chain as the ordinary fashioning means. As also described in U. S. Patent No. 1,902,151, the traversing speed may be kept substantially constant 30 and the frequency with which courses are knitted made substantially inversely proportional to the lengths of the courses, in order to give the machine a high output.

35 The lead changing means according to the invention may be adopted for use upon a great variety of weft knitting machines. For example, the device may be applied to a machine of the sliding needle type having bearded needles, wherein after yarn has been fed to the needles 40 sinkers pass successively through the spaces between the needles to sink loops of thread round the needles after which the needles are drawn down and raised up by the needle operating cams to knit and clear the loops. Or again if sliding 45 latch needles are used, the yarn is fed to the needles in advance of the knitting cams, which then operate directly upon the needles to draw loops of thread, generally without the use of sinkers. Further, the device is applicable to machines of the straight bar type, wherein yarn is fed successively to the needles, and loops of yarn are subsequently sunk round the needles by means of sinkers, knitting occurring on all the 50 needles at once when the sinking of loops along 55

the whole length of the machine has been completed. Since it is necessary that the yarn should be fed to the needles in advance of all other operations, it will readily be understood that the 5 yarn guide should be positioned with a definite lead over the cams operating upon the thread (sinker cams) or upon the needles (knitting cams). The device according to the present invention is adopted to control the movement of the 10 yarn guide, and positively to reverse the lead at each end of the knitting traverse.

While the invention is described with reference to the direct operation of the yarn guide, it will be understood that it may be applied to any 15 mechanism which itself actuates one or more yarn guides in conjunction with selective mechanism for feeding different yarns to the needles as desired.

The invention will now be described in greater 20 detail with reference to the accompanying drawing which illustrates the invention in connection with a knitting machine of the kind described in U. S. Patent No. 1,902,151, and in connection with the sinker cam driving mechanism described in 25 U. S. Application S. No. 580,597 filed Dec. 12, 1931. It is to be understood however that this description is given by way of example only, and is in no respect limitative.

Figure 1 is a rear elevation of the mechanism 30 according to the invention as applied to a knitting machine of the kind described in U. S. Patent No. 1,902,151.

Figure 2 is a plan view and Figure 3 a side elevation in section through the line 3—3 of Figure 1.

Figure 4 shows a modification of the yarn guide driving mechanism illustrated in Figure 1.

Referring to Figures 1, 2 and 3, a series of needles 11 shown clearly in Figure 3, are mounted in a needle bed 12 and are operated by means of cams 13, carried in a cam box 14 sliding upon a horizontal bar 15. The cam box 14 is driven by means of a mechanism comprising a cam box carriage 17 which is provided with a disc 18, of which a segment 19 is cut away (at the top of the disc as shown), the disc 18 being mounted upon a horizontal bar 20. The carriage 17 also carries four pulleys 21 mounted upon shafts 22 symmetrically disposed around the disc 18. The belt 23 runs freely between the pulleys 21 and the cut away portion 19 of the disc 18, but on the other side of the disc (as illustrated the lower side), the belt 23 is nipped between the disc 18 and pulleys 21. The belt 23 runs round a pair of pulleys 24, of which one is shown to the right of Figures 1 and 2, and is driven by mechanism (not shown) lying to the left of these figures. The disc 18 is prevented from rotating by means of a crank 25 rigidly fixed to it, whose free end bears upon two horizontal bars 26, 27 adjustably mounted upon a bar 28. For this reason, the motion of the belt 23 drives the carriage 17 and the disc 18, the cam box 14 being driven from the disc 18 by means of a pin 29 fixed into a block 30 situated in a slot 31 in the rear face of the cam box. When the cam box reaches the end of its traverse, the crank member 25 slips over the end of the bars 26 and 27 allowing the disc 18 to rotate for half a revolution which brings the cut away portion 19 of the disc 18 opposite the other run of the belt 23, and the block 30 and pin 29 to the other end of the slot 31. In this manner, the carriage 17 is clamped to the other run of the belt and is driven in the opposite direction, the process being repeated in reverse at the other end of the traverse. The sinkers 34 mounted in a bed 33

are operated by means of cams 35, 36 which proceed in lead of the knitting cams 13. The lead of the sinker cams is reversed at the end of the knitting traverse in the manner described in U. S. Application S. No. 580,597, Filed December 12, 1931. This specification describes in detail the mechanism shown generally in the drawing, by means of which the cams 35 and 36 move slightly in the direction of knitting relatively to the knitting cams and, at the same time, exchange functions, so that the effective lead is considerable. Means are also described for changing the lead of the presser cams. Two such cams, 55 and 56, are provided, one of which operates on the beards of the needles 11, while the other swings back to an inoperative position, the position being reversed when the direction of knitting is reversed. In co-operation with the sinker cam lead change and the presser cam lead change mechanism referred to above, means are provided according to 20 the invention for reversing the lead of the yarn guide.

Yarn is supplied from yarn guides 60 sliding upon bars 61, and operated by fingers 62 sliding upon bars 63. While in this description the members 60, 62 are described as sliding to and fro on the bars 61, 63, an arrangement convenient for a single machine producing one article at a time, these members may be rigidly fixed to the bars, which are then caused to slide bodily in their 30 bearings on the end frames 66 of the machine. This arrangement is convenient where a series of machines producing a number of articles simultaneously are driven from common driving means, the bars 61, 63 extending past all the machines, 35 and carrying a set of guides 60 and fingers 62 for each of such machines. Similar considerations apply to the bar 15 on which the knitting cams have been described as sliding.

The fingers 62 are mounted by a yarn guide 40 carriage 64 mounted upon a bar 65 and pushed from end to end of the machine in lead of the knitting cam, so that yarn is fed to the needles before the knitting cams operate upon them. For this purpose two cams 67, 68 are carried by an 45 enlargement 69 of the upper shafts 22 on the knitting cam carriage 17. The cams 67, 68 are respectively engaged by two levers 70, 71 pivoted to the yarn guide carriage 64 and each cam is provided with a V shaped notch 72, 73 which are engaged by bowls 75, 76 at the lower ends of the levers 70, 71. When the knitting cams are moving to the right, as shown, the bowl 75 on the right hand lever 70 is engaged in the notch 72 of its own cam 67 while the bowl 76 on the other 50 lever 71 rides upon the horizontal upper surface of its cam 68. At the end of the traverse, the bowl 75 attached to the lower end of the lever 70 engages with a stop 77 carried by the horizontal bar 27, and is thereby prevented from moving further to the right. The bowl 75 is therefore compelled to ride up the V shaped notch to the top of the cam 67, while the cams 67, 68 move on beneath it with the knitting cams 13, until the bowl 76 on the other lever 71 drops into the notch 73 55 of the other cam 68. The knitting cams 13 now come to rest at the end of the traverse and move in the reverse direction, that is to the left, the bowl 76 of the lever 71 being in engagement in the notch 73 of the cam 68 ready to drive the yarn guides to the left in lead of the knitting cams 13 as desired. At the other end of the knitting traverse the operation is reversed, the stop 77 engaging with the bowl 76 and causing it to become 70 75

disengaged from the notch 73 so that the bowl 75 can engage again with the notch 72.

In order to adjust the amount of lead imparted to the yarn guide the cams 61, 68 are slidably adjustable on their supports 69, in order that the respective positions of the two notches 12, 13 may be adjusted. Slots 79 are provided in the cams to allow of their adjustment. Alternatively however, adjustment may be made by moving the pivot points 80, 81 of the two levers 10, 11, and means for this purpose are illustrated in Figure 4, wherein slots 82, 83 are provided in which the pivot points 80, 81 may be adjusted. In this case, since adjustment of the cams is unnecessary the two cams can be made in one piece as illustrated at 85 in Figure 4. In this figure, instead of providing V notches in the cams, ramps 86, 87 are provided for the bowls 75, 76 to ride up at the ends of the traverse.

In each of the cases shown in Figs. 1 and 4, the levers 10, 11 when in engagement with the notches 72, 73 or the ramps 86, 87 lie substantially at right angles to the working surfaces of such notches or ramps. This is the optimum angle, since the drive of the yarn guide is thereby made positive, there being no tendency for the bowls 75, 76 to run up the slopes until they are engaged by the stops 77, 78 while at the same time, when such engagement does occur there is no acceleration of the yarn guide due to the rising of the bowls 75, 76, but a gradual deceleration, a desirable feature, especially in machines working at high speed.

As described in U. S. Patent No. 1,902,151, the position of the ends of the bars 26 and 27 is automatically adjustable for the production of fashioned articles. Since the stops 77, 78 are mounted with the bars 26, 27, these stops are also adjusted simultaneously with the bars 26, 27, and the number of needles to which yarn is fed is adjusted. A further feature in common use in knitting machines of this type, is a selective mechanism for determining what kind of yarn shall be fed to the needles. Such a mechanism may be employed in association with the fingers 62, to bring selected finger into engagement with the corresponding yarn guides 60. Only two of such guides 60 are shown, but more may be employed, mounted on further bars 61 in the position indicated in Figure 3. Two or more selected yarns may be fed to the needles simultaneously by means of the selecting mechanism referred to above.

What we claim and desire to secure by Letters Patent is:—

55 1. Flat knitting machine comprising sliding means for effecting a knitting traverse, sliding means for carrying a yarn guide, a pair of links pivotally mounted on said yarn guide carrying means, said links being adapted to swing in a plane parallel to the direction of traversing, a pair of ramps on said traversing means adapted to engage in turn with the ends of said links to traverse the yarn guide in lead of the knitting traverse, and a stop at each end of the knitting traverse adapted to engage the end of the driving link to prevent further traversing motion thereof and to cause the link to swing so that the said end rides up the ramp and becomes disengaged therefrom, whereby the other link may engage with the other ramp after the yarn guide has been at rest long enough to reverse its lead over the knitting traverse, preparatory to traversing in the opposite direction, and means for adjusting the distance between said ramps so as to adjust the amount of lead of the yarn guide over the knitting traverse.

70 2. Flat knitting machine comprising sliding means for effecting a knitting traverse, sliding

means for carrying a yarn guide, a pair of links pivotally mounted on said yarn guide carrying means, said links being adapted to swing in a plane parallel to the direction of traversing, a pair of ramps on said traversing means adapted to engage in turn with the ends of said links to traverse the yarn guide in lead of the knitting traverse, and a stop at each end of the knitting traverse adapted to engage with the end of the driving link and prevent further traversing motion thereof, whereby the said end is caused to ride up the ramp, the pivoting motion of the link thereby engendered continuing to move the yarn guide at a diminishing rate until it comes to rest so that the other link may engage with the other ramp after the yarn guide has been at rest long enough to reverse its lead over the knitting traverse preparatory to traversing in the opposite direction.

3. Flat knitting machine comprising sliding means for effecting a knitting traverse, sliding means for carrying a yarn guide, a pair of links pivotally mounted on said yarn guide carrying means, said links being adapted to swing in a plane parallel to the direction of traversing, a pair of ramps on said traversing means adapted to engage in turn with the ends of said links to traverse the yarn guide in lead of the knitting traverse, a stop at each end of the knitting traverse adapted to engage the end of the driving link to prevent further traversing motion thereof and to cause the link to swing so that the said end rides up the ramp and becomes disengaged therefrom, whereby the other link may engage with the other ramp after the yarn guide has been at rest long enough to reverse its lead over the knitting traverse preparatory to traversing in the opposite direction, and means for adjusting the amount of lead of the yarn guide over the knitting traverse.

4. Flat knitting machine comprising sliding means for effecting a knitting traverse, sliding means for carrying a yarn guide, a pair of links pivotally mounted on said yarn guide carrying means, said links being adapted to swing in a plane parallel to the direction of traversing, a pair of ramps on said traversing means adapted to engage in turn with the ends of said links to traverse the yarn guide in lead of the knitting traverse, a stop at each end of the knitting traverse adapted to engage the end of the driving link to prevent further traversing motion thereof and to cause the link to swing so that the said end rides up the ramp and becomes disengaged therefrom, whereby the other link may engage with the other ramp after the yarn guide has been at rest long enough to reverse its lead over the knitting traverse, preparatory to traversing in the opposite direction, and means for adjusting the distance between said ramps so as to adjust the amount of lead of the yarn guide over the knitting traverse.

5. Flat knitting machine comprising sliding means for effecting a knitting traverse, sliding means for carrying a yarn guide, a pair of links pivotally mounted on said yarn guide carrying means, said links being adapted to swing in a plane parallel to the direction of traversing, a pair of ramps on said traversing means adapted to engage in turn with the ends of said links to traverse the yarn guide in lead of the knitting traverse, a stop at each end of the knitting traverse adapted to engage the end of the driving link to prevent further traversing motion thereof and to cause the link to swing so that the said

end rides up the ramp and becomes disengaged
therefrom, whereby the other link may engage
with the other ramp after the yarn guide has been
at rest long enough to reverse its lead over the
knitting traverse preparatory to traversing in the
opposite direction, and means for adjusting the

distance between said stops so as to adjust the
length of the knitting traverse.
